UNITED STATES PATENT OFFICE.

PERRY SPEELMAN HOUGHTON, OF LINDSEY, PENNSYLVANIA.

PISTON-ROD FOR STEAM-PUMPS.

SPECIFICATION forming part of Letters Patent No. 636,668, dated November 7, 1899.

Application filed June 16, 1899. Serial No. 720,795. (No model.)

To all whom it may concern:

Be it known that I, PERRY SPEELMAN HOUGHTON, of Lindsey, in the county of Jefferson and State of Pennsylvania, have invented a new and Improved Piston-Rod for Steam-Pumps, of which the following is a full, clear, and exact description.

The object of the invention is to provide a new and improved piston-rod for steam-pumps which is simple and durable in construction, very cheap to manufacture, and not liable to break, bend, or spring when in use.

The invention consists of novel features and parts and combinations of the same, as will be fully described hereinafter and then pointed out in the claim.

Reference is to be had to the accompanying drawing, forming a part of this specification, in which the figure is a sectional side elevation of the improvement as applied.

Piston-rods as now employed in steam-pumps are usually made of solid brass or bronze, and hence are quite expensive and are liable to bend or spring when the pump is in working heavily.

In order to cheapen the cost and to strengthen the piston-rod, I provide a steel or iron core A in the form of a solid rod cast in the brass or bronze piston-rod proper, B, to

stiffen the piston-rod and to prevent it from bending upon the push-stroke of the pump. The core A is formed with annular recesses A' for the brass or bronze metal of the rod proper, B, to fill when casting the piston-rod to prevent the brass from breaking and pulling on the iron or steel core upon the draw-stroke of the pump. The ends A² of the core are preferably pointed, as shown in the drawing, to permit of readily centering the core when casting the piston-rod, so as to bring the core perfectly true in the center of the rod B.

Having thus fully described my invention, I claim as new and desire to secure by Letters Patent—

A piston-rod for steam-pumps, the rod having a core formed of iron or steel and provided with annular grooves or recesses extending around it, and a rod proper formed of brass, bronze or the like and inclosing the core, the rod proper being cast integral around the core and having portions run into grooves and recesses thereof to form a compact inseparable mass.

PERRY SPEELMAN HOUGHTON.
